CASING FOR AN ELECTRIC MOTOR

Jacobus Constant van Rijn, Woodstock, N. Y., assignor
to Rotron Manufacturing Co., Inc., Woodstock, N. Y.,
a corporation of New York

Application April 14, 1954, Serial No. 30,018

Term of patent 14 years

(Cl. D26—5)

FIG. 1

FIG. 2

FIG. 3

FIG. 4

To all whom it may concern:

Be it known that I, Jacobus Constant van Rijn, a citizen of the United States and a resident of Woodstock, in the county of Ulster and State of New York, have invented a new, original, and ornamental Design for a Casing for an Electric Motor, of which the following is a specification, reference being had to the accompanying drawing, forming a part hereof.

Figure 1 is a front perspective elevation of a casing for an electric motor, showing my new design;

Figure 2 is a front elevation thereof;

Figure 3 is a side elevation thereof; and

Figure 4 is a side perspective view along line 4—4.

of Fig. 2 and looking from a point above an electric motor casing according to my new design.

I claim:

The ornamental design for a casing for an electric motor, as shown and described.
